UNITED STATES PATENT OFFICE.

CHARLES ZABEL, OF CORAOPOLIS, PENNSYLVANIA, ASSIGNOR, BY MESNE ASSIGNMENTS, TO McDOWELL MANUFACTURING COMPANY, OF MILLVALE, PENNSYLVANIA, A CORPORATION OF PENNSYLVANIA.

MECHANICAL TOY AND METHOD OF MAKING SAME.

Application filed September 27, 1923. Serial No. 665,115.

This invention is for an improved wheeled toy and a method of making the same.

The invention relates particularly to a wheeled toy adapted to be used in connection with some mechanical toy having some kind of a track which is tilted, so that the wheeled toy or car will gravitate along the track. Such a toy is shown, for instance, in my Patent No. 1,469,710, dated October 2, 1923. I do not confine myself, however, to the use of the present invention with the particular toy shown in said application.

Toys of this nature must be made as cheaply as possible, in order to be sold at the low price demanded for them. Consequently, they must be so constructed that they may be rapidly assembled in large quantities, each article being capable of operating successfully when assembled. A wheeled toy for this purpose is, furthermore, more attractive if it is provided with moving figures.

A great difficulty encountered where moving figures are used is that, heretofore it has been the practice to use rivets to provide pivots for moving parts. When rivets are used, great care must be taken in assembling the toy; otherwise there is so much friction between the parts as to cause the toy, which is very light, not to operate free enough to let the toy gravitate at the necessary speed required to keep pace with the tilting motion of the tracks. If such care must be taken in making the cars, the cars cannot be produced fast enough and cheap enough to make the toy very practical, commercially.

The present invention has for its principal object to provide a novel toy or car having moving figures therein operated by the motion of the car, and which may be cheaply made, the parts preferably being so assembled that the use of rivets in the moving parts is eliminated.

A further object of the invention is to provide a novel method of making the cars.

The invention may be readily understood by reference to the accompanying drawings, in which:

Fig. 1 is a side elevation of the car, the view being the actual size of the toy;

Fig. 2 is a longitudinal section along the center of the car shown in Fig. 1, but on an enlarged scale;

Fig. 3 is a plan view of the arms for the figures as originally formed;

Fig. 4 is a top view of the arms when finished; and

Fig. 5 is a side view of one of the figures illustrating the manner of attaching the arms and legs to the body.

In the drawings, 5 designates a platform pressed from sheet metal, having downwardly turned integral axle receiving lugs 6 thereon. These lugs carry the two axles 7 and 8, on which are fixed wheels 9. Axle 7 is formed with a central crank 10, shown in Fig. 2, for the purpose hereinafter described.

Formed in the platform along the longitudinal center thereof over each axle, is a slot 11 and 12, respectively. Carried on the platform, with the lower extremities thereof engaging in the respective slots, are miniature figures 13 and 14 having leg members 15 and arm members 16.

The arm members for each figure are formed of a piece of sheet metal, of the shape shown in Fig. 3, having two arm portions 16^a connected by a narrow strip 16^b. The strip shown in Fig. 3 is bent to the shape shown in Fig. 4.

Each of the bodies 13 and 14 has a rectangular hole 17 punched in the shoulder portion thereof. The metal from the nearest outside edge of the body to the hole is cut, as indicated at 18. After the arms have been bent, as shown in Fig. 4, the metal at one side of cut 18 is bent to one side, as indicated at 19 in Fig. 5. The connecting strip of the arms may then be inserted through the cut into hole 17, and the bent part 19 returned to its normal position, as in Fig. 1. The arms are thus attached to the body in such manner that they may swing relatively thereto.

The legs 15 are formed in the same manner as the arms, a neck portion 21 connecting the two legs of each figure in the same manner that the arms are connected. The connecting portion is inserted in the same way as the arms in an opening 22 near the

base of the body, the metal being cut at 23 to enable the connecting portion to be inserted.

The legs are provided with lugs 24 which 5 bend under the platform. The figures are thus supported in sitting position by the legs.

In the outer ends of the arms are holes 25 through which cross bar 26 of post 27 extends. The cross bar thus connects the arms of the two figures, so that the two figures may rock in unison. Post 27 has a lug 28 on its lower end, as shown in Fig. 2, which passes through the platform and is turned 15 over. This slot in the platform is sufficiently loose to enable the post to rock back and forth in a longitudinal plane.

The bodies of one of the figures 13 is extended down through the platform and has a 20 bifurcated end which straddles the crank 10 on axles 7. Thus, when the toy moves, axles 7 are rotated, rocking figure 13, movably supported on its legs, back and forth, and this motion is transmitted to post 27 and to the 25 other figure 14.

It will be apparent that from the manner of assembling the arms and legs, plenty of freedom of movement exists between the various parts. Such freedom cannot be 30 consistently obtained where rivets are used, as the rivets cannot be readily set in a press in such a way as not to cause considerable friction between the parts. As the toys are

operated by gravity and weight but very little, weighing in the average toy about an 35 ounce, it is essential that the parts be as free as possible.

When the car is in motion, it gives the appearance of two men operating a hand car, 40 of which post 27 is the operating handle.

I claim as my invention:

A toy comprising a platform, a pair of figures carried on the platform, said figures each having a body portion and a pair of legs, said legs having an integral cross member connecting their upper ends, said connecting member engaging loosely in an opening in the figure, the legs being secured to the platform, a rocking support being provided for each figure by the legs, a pair of arms on each figure, said arms being integrally formed and connected by a relatively narrow strip, the body of each figure having a slot therein for the reception of the connecting strip of its arms, a pair of axles under the 45 platform with wheels thereon, one of the axles having an eccentric, and a bifurcated extension on one of the figures passing through a slot in the platform and having its bifurcated end astraddle the said eccentric 50 of one of the axles, and means connecting the arms of the two members whereby they may rock in unison.

In testimony whereof I affix my signature.

CHARLES ZABEL.
